C. TANNEBAUM

POCKET GUARD

Filed Dec. 30, 1927

UNITED STATES PATENT OFFICE.

CARL TANNEBAUM, OF NEW YORK, N. Y.

POCKET GUARD.

Application filed December 30, 1927. Serial No. 243,716.

This invention relates to improvements in pocket guards.

The primary object of the invention resides in a guard or protective device for attachment 5 to the pocket of a garment for safeguarding the contents of the pocket, such as bills, checks, tickets and the like from theft or accidental loss.

Another object of the invention is to provide 10 a pocket guard adapted to be removably clamped upon the wall of a pocket so as not to interfere with access to the interior of the pocket when desired but which holds the contents of the pocket against theft or loss 15 as any attempt by a pickpocket to remove the valuables will be instantly detected.

A further object is the provision of a pocket guard which is simple of construction, 20 easy to apply and remove from the pocket by the wearer, and which is practical and efficient for every day use by persons who carry paper money and like valuables.

With these and other objects in view, the invention resides in certain novel construction 25 and combination and arrangement of parts, the essential features of which are hereinafter fully described, are particularly pointed out in the appended claim, and are illustrated in the accompanying drawing, in 30 which:—

Figure 1 is a perspective view of my improved pocket guard.

Figure 2 is a side elevation thereof.

Figure 3 is a vertical longitudinal sectional view therethrough showing the same 35 in an applied position upon a pocket.

Referring particularly to the drawing, the reference numeral 10 designates my improved pocket guard in its entirety, which includes 40 a flat elongated body member 11 having one of its ends looped and bent upon itself to provide an arm 12. Pivoted to the free end of the arm 12 as at 13 is a clamp 14 which includes a jaw 15 and a tail or manipulating 45 arm 16. Both the jaw and tail co-act with the body 11 to clamp the guard to the wall 17 of a pocket 18 as shown in Figure 3 of the drawing.

The body 11 is provided with an elongated 50 slot 19 therein for slidably receiving the shanks of headed studs 20 which extend from the back of a spring clip 21. The clip 21 has

a flat straight portion 22 which is slidable over the back of said body member 11 and a resilient spring bill or jaw 23 which tends 55 to clamp any flat article to be held against the straight portion 22 of the clip.

In practice, the paper money, tickets or the like to be protected are clamped between the jaw 23 and the adjacent portion of the clip, 60 after which the guard is inserted into the pocket so that the clamp 14 clamps the protector to one of the walls thereof adjacent the mouth of the pocket. Upon insertion of the pocket guard into the pocket, the weight of 65 the clip and the articles held thereby tends to drop to the bottom of the pocket away from the open mouth thereof. The valuables are securely held against accidental loss through the mouth of the pocket and any attempt to 70 slide the clip outward toward the mouth to remove the valuables held thereby will be readily detected.

It is believed that a pocket equipped with 75 a guard such as shown and described will assure the safe carrying of valuables. Should the wearer desire to remove any of the valuables held by the clip, he unfastens the clamp 14 and slides the protector out through the mouth of the pocket whereupon the valuables 80 may be removed from under the clip.

While I have described what I deem to be the most desirable embodiment of my invention, it is obvious that many of the details may be varied without in any way departing 85 from the spirit of my invention, and I therefore do not limit myself to the exact details of construction herein set forth nor to anything less than the whole of my invention limited only by the appended claim. 90

What is claimed as new is:

A pocket guard comprising an elongated body member bent upon itself at one end to provide an arm, a clamping device pivoted to said arm and adapted to co-act with said body member for clamping the wall of a pocket therebetween, said elongated member having an elongated slot therein, and a spring clip provided with headed pins extending through said slot for slidably mounting said 100 clip upon said body member.

In testimony whereof I have affixed my signature.

CARL TANNEBAUM.
